ABSTRACT OF THE DISCLOSURE

An impulse propulsion wheel for boats and the like having a plurality of blades spaced around the circumference of a wheel and having open spaces between them. The blades being shaped to have at least two distinct radii of curvature on the face of the blade and being mounted to have the greatest curvature nearest the center of the wheel and to have the tip of the blade enter the water at substantially right angles to the surface of the water at the design speed.

The invention described herein may be manufactured and used by or for the Government of the United States of America for governmental purposes without the payment of any royalties thereon or therefor.

BACKGROUND OF THE INVENTION

The invention is related to propulsive devices of the paddle wheel type in which the propulsive force is proportional to the change in speed and the mass of the water moved by wheel. Such basic concepts are taught by the inventor's Pat. No. 3,251,334 and the patent to Lord, No. 484,503.

The present invention is an improvement in the construction of the paddle wheel or impulse turbine to provide for greater efficiency in operation than has been disclosed in the prior art.

OBJECTS OF THE INVENTION

It is an object of this invention to provide efficient shallow water propulsion.

Another object is to improve the efficiency of a propulsion wheel by limiting the spill of the water toward the axis of the wheel.

Another object is to prevent the entrapment of air by the blade as it enters the water.

Another object is to provide continuous acceleration of the water toward the rear as the blades enter the water.

Another object of the invention is to provide for the release of the water from the blade as the blades move out of the water.

Still another objective of the present invention is to minimize the energy loss due to the impact of the blades entering the water.

Other objects, advantages and novel features of the invention will become apparent from the following detailed description of the invention when considered in conjunction with the accompanying drawings wherein:

BRIEF DESCRIPTION OF THE DRAWINGS

FIG. 1 is a diagrammatic showing of the wheel of this invention with the near end of the wheel removed and the structure of the interior shown in part.

FIG. 2 is a diagram showing the profile shape of the blade of a preferred embodiment of the invention.

FIG. 3 illustrates a modification of the blades of FIG. 2 in which the blade is vented by being made in two parts.

FIG. 3a is a vector diagram of the velocities associated with the blade, e.g. the blade of FIG. 3.

2

FIG. 4 illustrates a second modification of the blade of FIG. 2 in which there are provided steps in the blade and holes for venting the blade.

**DESCRIPTION OF THE PREFERRED
EMBODIMENT**

Referring now to the drawing wherein like numerals refer to the same or corresponding parts in the several views wherein are shown preferred embodiments of the invention, there is shown in FIG. 1 a plurality of blades 11 mounted around the periphery of the wheel 10 by any suitable means, such as welding, riveting, etc. The wheel 10 is mounted for rotation on a suitable vehicle, boat, Captured Aire Bubble Vehicle, etc. (not shown) and is driven by a suitable power system (not shown) in the direction shown by the arrow 12 in FIG. 1. These blades 11 are mounted with open spaces between them and with the inner edge 13, the edge nearest the axis of the wheel, substantially perpendicular to a radius of the wheel which passes through the blade as shown by line 20 in FIG. 2. The tip edge 14 or edge of the blade farther from the axis of the wheel 10 is positioned such that at the point of entry into the surface of the water, when the water is in a quiet state, the blade enters substantially at right angles to the surface of the water. The wheel is so mounted in the vehicle, that for quiet water conditions inner edge 13 does not enter below the water level, or is not submerged as the wheel 10 rotates.

As seen in FIG. 2 the blade 11 is constructed with at least two different radii of curvature. These radii are selected to provide a continuous acceleration of the water rearward as the wheel rotates and the blades move deeper into the water. After the blades begin to move out of the water the rearward component of the velocity reduces but continues to impart some force to the entrained water until the water spills out of the blades. The mounting of the blades with the inner edge perpendicular to the radii of the wheel and with some short extension beyond the radius to which it is perpendicular is to prevent the water from escaping from the blade into the interior of the wheel. While the spaces between the blades allow the air displaced by the water to escape.

The tip edge 14 of the blade 11 is sharpened to minimize the loss of efficiency associated with the impact of the blade as it enters the water surface.

The vector diagrams shown in respect to several of the blades as seen in FIG. 1, indicate the instantaneous relative direction and magnitude of the vertical and horizontal components of velocity as the wheel rotates, but does not reflect the effect of the horizontal movement of the wheel axis as the vehicle moves. In practice, to achieve the desired angle of entry of the blades into the water the design speed of the vehicle must be considered. In which case the angle of entry may not be exactly perpendicular to the surface of the water, the design being optimized for the design speed.

The shape of the blade may be described as having a profile such that the plane in which the blade face at the tip lies will be in advance of the axis of rotation of the wheel and as said plane is moved over the surface of the blade toward the axis of rotation of the wheel the plane is rotated in the opposite direction to the rotation of the wheel until at the point of closest proximity to the axis of rotation of the wheel the plane will be perpendicular to the radius of the wheel at that point.

Referring to FIG. 2 there is illustrated a method of designing the blade structure wherein the line 20 represents a radius of the wheel and the two radii of curvature of the concave surface are shown as being related as two to one, that is, the long radius of curvature is

twice the length of the short radius of curvature. Of course, other relationships may be selected and more than two radii may be used, even a continuously varying radius curvature may be ideally used.

The modification of FIG. 3 shows the blade as having a venting slot 21 to aid in the escape of the air displaced by the water as the wheel turns and to facilitate the release of the water carried by the blade by allowing air to enter through the slot as the water spills out of the blade. The small vector diagram of FIG. 3a wherein vector 22 represents the velocity of the blade, vector 23 represent the desired velocity of the water and vector 24 is the resultant of vectors 22 and 23 and represents the desired velocity of the water relative to the blade.

In FIG. 4 the improved efficiency is accomplished by creating within the concave curvature of the blade a series of steps 26 which may be vented by opening 27 through the blade.

Obviously many modifications and variations of the present invention are possible in the light of the above teachings. It is therefore to be understood that within the scope of the appended claims the invention may be practiced otherwise than as specifically described.

What is claimed is:

1. In a paddle wheel propulsion device for fluid borne vehicles:

a power driven wheel having a plurality of peripherally mounted equally spaced blades on said wheel; each of said blades having a face, concave in the direction of rotation of said wheel, the curvature of said concave face increasing the acceleration of the

fluid as said blades progressively enter the surface of said fluid; and

said curvature of said concave face is varied to include at least two different radii of curvature so that the tip edge of the blade has a radius of curvature greater than the inner edge of the blade.

2. A device as claimed in claim 1 in which a portion of the blade is stepped on the concave face.

3. A device as claimed in claim 1 in which said blades are ventilated by openings located nearer to the inner edge than to the tip of the blades.

4. A device as claimed in claim 3 in which a portion of the blade is stepped on the concave face.

5. A device as claimed in claim 3 wherein said ventilated opening comprises a slot.
